UNITED STATES PATENT OFFICE.

FRANK W. CALVERT, OF NARBERTH, PENNSYLVANIA, ASSIGNOR TO THE CHARLES E. HIRES COMPANY, OF PHILADELPHIA, PENNSYLVANIA, A CORPORATION OF PENNSYLVANIA.

DESIGN FOR A LIQUID-DISPENSING FOUNTAIN.

40,558.

Specification for Design.

Patented Mar. 1, 1910.

Application filed August 19, 1908. Serial No. 449,386. Term of patent 14 years.

To all whom it may concern:

Be it known that I, FRANK W. CALVERT, a citizen of the United States, and a resident of Narberth, Montgomery county, Pennsylvania, have invented a certain new, original, and ornamental Design for a Liquid-Dispensing Fountain, reference being had to the accompanying drawing, forming part thereof, showing a perspective view illustrating my design for a liquid-dispensing fountain.

My design comprises a curved arm structure extending from an ornamental base and having at its upper end a rectangular shell from which an ornamental tube depends and

from the top of which a bent arm terminating in a ball extends toward the front. Surmounting said rectangular box-like portion is an ornamental shell having a bulging central part upon which is mounted a syrup jar, semi-spherical in shape, surrounded by an ornamental cap.

I claim:

The ornamental design for a liquid dispensing fountain as shown and described.

FRANK W. CALVERT.
